UNITED STATES PATENT OFFICE.

GEORGE PETERSON, OF NEW AUBURN, WISCONSIN.

SHOVEL ATTACHMENT FOR PITCHFORKS.

1,220,453.

Specification of Letters Patent. Patented Mar. 27, 1917.

Application filed October 30, 1916. Serial No. 128,518.

To all whom it may concern:

Be it known that I, GEORGE PETERSON, a citizen of the United States, residing at New Auburn, in the county of Chippewa and State of Wisconsin, have invented certain new and useful Improvements in Shovel Attachments for Pitchforks; and I do declare the following to be a full, clear, and exact description of the invention, such as will enable others skilled in the art to which it appertains to make and use the same.

This invention has general reference to the broad class of tools, but relates specially to shovel attachments for stable or pitch forks.

The primary object of the invention is to provide a shovel blade which may be easily and readily attached to the ordinary stable or pitch fork, and just as readily removed therefrom.

Another object of the invention is to generally improve upon attachments of this character by the provision of a simple, strong, durable and inexpensive construction and a device which is well adapted to the purpose for which it is designed.

With these and other objects in view, the invention resides in the novel features of construction, combination and arrangement of parts as will be hereinafter fully described and claimed.

In the accompanying drawings forming a part of the application and in which similar reference characters designate like parts throughout the several views:

Figure 1 is a front elevation of a shovel blade constructed in accordance with this invention, showing the same applied to an ordinary pitch fork;

Fig. 2 is a longitudinal sectional view through the shovel blade applied to the pitch fork taken on the plane of the line 2—2 of Fig. 1;

Fig. 3 is a transverse sectional view of the same taken on the plane of the line 3—3 of Fig. 1; and,

Fig. 4 is a transverse section through the clamp at the upper end of the blade taken on the plane of the line 4—4 of Fig. 2.

Referring more particularly to the drawings, the reference numeral 1 designates a shovel blade made preferably of sheet metal stamped into any desired shape, and having its lower edge bent under upon itself as at 2 and stamped outwardly at transversely spaced distances to form in connection with

the blade proper 1, longitudinally extending sockets 3, the purpose of which will be hereinafter described. The blade 1 is substantially of a length equal to that of the pitch fork in connection with which it is designed to be used.

Arranged midway of the width of the blade 1 at the upper end thereof and extending longitudinally relatively to the same is a U-shaped resilient clamp 4, the lower end of which is provided with an extension 5 having a hinged connection 6 with the upper end of the blade 1. As shown, this hinged connection is disposed upon the upper side of the blade 1 and has its axis arranged in parallel relation with respect to the lower edge of the blade. The open side of the clamp 4 is disposed rearwardly, the purpose of which will be hereinafter described. At the other end of the clamp 4 is an angularly disposed extension 7 which forms a thumb piece for a hereinafter to be described purpose.

A blade constructed in this manner is designed particularly to be attached to an ordinary stable or pitch fork, and in this connection Fig. 2 of the drawings shows it applied thereto. In this figure the tines 8 of the fork are disposed adjacent the lower side of the blade 1, the points of the former being received in the sockets 3 at the lower end of the latter, while the handle 9 of the fork is engaged by the clamp 4, said clamp 4 being swung on its pivot toward said handle to effect this engagement. The cross bar 8 connecting the tines at the upper end of the fork is engaged by the lower or inner edges of the arms of the clamp 4, when the latter is in its operative position. When in this position the inner edges of the arms of the clamp extend substantially at right angles to the upper portion of the back of the blade as shown in Fig. 2. This prevents the tines of the fork from accidentally sliding longitudinally out of the sockets in the blade. When it is desired to remove the blade from the fork, it is only necessary to grasp the thumb piece formed by the extension 7 and move the clamp away from the handle of the fork, and then slide the blade downwardly or longitudinally with respect to the tines of the fork.

A device constructed in accordance with this invention will be found very useful upon farms and numerous other places, as an ordinary pitch fork can be easily and in-

stantaneously converted into a shovel, and when used as a shovel can be easily and instantaneously taken down to again form a pitch fork. The various uses of the two interchangeable implements will be appreciated.

From the foregoing description, taken in connection with the accompanying drawing, the construction, advantages and use of the 10 invention will be readily understood without a more extended explanation.

As numerous changes in form, proportion, and in the minor details of construction may be resorted to without departing from 15 the spirit of this invention, it is to be understood that I do not wish to be limited to the construction herein shown and described other than that set forth in the appended claim.

20 I claim:—

A shovel attachment for pitch forks comprising a shovel blade of a length substantially equal to the length of the pitch fork in connection with which it is to be used,

25 sockets arranged at the lower end of said blade and on the under side thereof to receive the tines of the fork, and a resilient U-shaped clamp hinged on an axis parallel to the lower edge of said blade upon the upper side of the latter midway of its width 30 and at the upper end thereof, said clamp extending longitudinally with respect to said blade and having its open side disposed rearwardly to receive the handle of the fork, the inner edges of the resilient arms of said clamp extending substantially at right angles to the upper portion of the back of said blade when said clamp is in its handle-engaging position to engage the cross bar connecting the upper ends of the tines of 40 the fork.

In testimony whereof I have hereunto set my hand in the presence of two subscribing witnesses.

GEORGE PETERSON.
